(57) **CLAIM**

The ornamental design for a CD holder, as shown and described.

DESCRIPTION

FIG. 1 is a perspective view of the CD holder showing my design.

FIG. 2 is a front view thereof;

FIG. 3 is a back view thereof;

FIG. 4 is a side view thereof;

FIG. 5 is an opposite side view thereof;

FIG. 6 is a top view thereof;

FIG. 7 is a bottom view thereof; and,

FIG. 8 is an upper perspective view thereof, showing compact disks inserted therein.

The broken line showing of compact disks is for illustrative purposes only and forms no part of the claimed design.
